UNITED STATES PATENT OFFICE.

IDA K. SHIER, OF YPSILANTI, MICHIGAN.

DESIGN FOR A CASKET.

SPECIFICATION forming part of Design No. 25,445, dated April 28, 1896.

Application filed March 2, 1896. Serial No. 581,584. Term of patent 14 years.

To all whom it may concern:

Be it known that I, IDA K. SHIER, a citizen of the United States, residing at the city of Ypsilanti, in the county of Washtenaw and State of Michigan, have invented and produced a new and original Design for Caskets, of which the following is a specification, reference being had to the accompanying drawings, showing a part thereof.

10 Figure 1 is a perspective view of my design, the dotted lines showing the cover open. Fig. 2 is a cross-sectional view of the casket when open, and Fig. 3 is a cross-sectional view of the casket closed. These three views are deemed 15 necessary to fully illustrate my design.

The leading feature of my design consists in the conical shape of the casket, having a whirl at the larger end and a projecting lip extending the entire length of the casket, as 20 shown in Fig. 1.

The head of the casket is in the form of a whirl, which, commencing at the edge of the lip D, is coiled up into a spiral at the center c.

The lip D extends the entire length of the casket from the bottom upward and slightly 25 forward, so as to leave a space between the inside of the lip and the body of the casket, exposing the inside of the lip to view.

The bottom of the casket is flattened and the lip D extends from the front edge thereof, 30 as already stated and as is shown in the drawings.

It will be seen by the foregoing description and the accompanying drawings that the main contour of the casket is conical, and that the 35 design is substantially that of a hollow cone, the top part B comprising a little less than one half and the bottom A the other part thereof.

What I claim is—

The design for a casket substantially as shown and described.

IDA K. SHIER.
